INVENTOR

William G. Kett
BY
Harry S. Toller
ATTORNEY

UNITED STATES PATENT OFFICE.

WILLIAM G. KETT, OF OAKLAND, CALIFORNIA, ASSIGNOR OF ONE-HALF TO WILLIAM G. C. TURNER, OF SAN FRANCISCO, CALIFORNIA.

BUMPER.

Application filed December 16, 1924. Serial No. 756,199.

To all whom it may concern:

Be it known that I, WILLIAM G. KETT, a citizen of the United States, residing at Oakland, in the county of Alameda and State of California, have invented certain new and useful Improvements in Bumpers, of which the following is a specification.

The present invention relates to bumpers for automobiles and other like vehicles.

- 10 The object of the invention is to produce an improvement in bumpers of the nonhook type, which improvement consists essentially in the particular construction of the central or main contact bar and the mounting brackets extending therefrom, and also consists in the formation of the nonhook ends and their manner of attachment to the ends of the main bar, whereby a stronger and more efficient bumper of this type is provided.
- 15 20 With the above mentioned and other objects in view, the invention consists in the novel construction and combination of parts hereinafter described and illustrated in the accompanying drawings and pointed out in 25 the claims hereto appended, it being understood that various changes in form, proportion, size and minor details of construction may be resorted to without departing from the spirit or sacrificing any of the advantages of the invention.

To more fully comprehend the invention, reference is directed to the accompanying drawings, wherein—

Figure 1 is a fragmental plan view of the front end of an automobile showing the bumper attached thereto.

Figure 2 is a fragmental plan view enlarged showing one of the hinged members, in part only, the rear face being omitted.

40 Figure 3 is a vertical sectional view taken in the direction of the arrows on line 3—3 of Figure 2.

In the drawings, wherein like characters of reference designate corresponding parts, 45 1 indicates the central member of the bumper, constructed preferably of flat strap material, the ends 2 of which are turned backward and form a means of securing the central member 1 to the frame horns 3 of the 50 chassis of an automobile by means of the bolts 4 or other suitable attaching devices. The outer faces of the rearwardly bent ends

2 also form an abutment against which the end members 5 are adapted to lie when in assembled normal position. The end members 5 are made from suitable strap material and are substantially triangular in plan, their front faces 6 being shaped to continue the contour of the front face of the central member 1 their rear faces 7 being inclined toward the apex, as shown in Fig. 1, and their base faces 8 lying parallel with and abutting against the outer faces of the bent ends 2 of the central member 1.

The triangular end members 5 are secured to the ends of the central member 1 by means of a spring hinge 9, the tension of the spring being sufficient to hold the triangular end members 5 substantially rigid against the abutments formed by the bent ends 2 of the central member 1.

The operation of the end members 5 when struck by an impact from the rear is such that said members will yield forwardly to permit the vehicle to pass the obstruction, thus eliminating any possibility of the bumper being caught and displaced or injured.

After the obstruction has passed the end members 5 are returned to their normal position due to the tension of the spring hinge 9.

On the other hand, if the force of impact comes from the front, the same will be met by substantially rigid resistance due to the relatively extensive and solid abutments 2 and 8.

I claim:—

1. A bumper comprising a central member having rearwardly bent ends adapted for attachment to a vehicle frame; end members 90 consisting of substantially triangular sections the front faces of which are shaped to continue the face contour of the central member, their rear faces being inclined forwardly to an apex, and their base faces lying parallel with and abutting against the outer faces of the bent ends of the central member; and a spring hinge connection between said end members and the ends of the central member located in the line of their front faces, adapting said end members to yield forwardly only.

2. A bumper comprising a central member consisting of a flat faced bar with rear-

wardly bent ends integral therewith, adapted for attachment to a vehicle frame; end members each consisting of a flat faced bar bent to form a skeleton substantially triangular section the front faces of which are shaped to continue the face contour of the central member, their rear faces being inclined forwardly to an apex, and their base faces lying parallel with and abutting against the outer

faces of the bent ends of the central member; 10 and a spring controlled hinge connection between said end members and the central member located in the line of their front faces, adapting said end members to yield forwardly only.

In testimony whereof I have signed my name to this specification.

WILLIAM G. KETT.
